UNITED STATES PATENT OFFICE.

FREDERICK A. GILBERT, OF BROOKLINE, AND EMIL O. LUNDIN, OF BEACHMONT, MASSACHUSETTS, ASSIGNORS TO THE GENERAL ELECTRIC COMPANY, OF NEW YORK.

ELECTRIC-ARC LAMP.

SPECIFICATION forming part of Letters Patent No. 662,931, dated December 4, 1900.

Application filed July 22, 1898. Serial No. 686,576. (No model.)

To all whom it may concern:

Be it known that we, FREDERICK A. GILBERT, of Brookline, county of Norfolk, and EMIL O. LUNDIN, of Beachmont, county of Suffolk, State of Massachusetts, have invented 5 an Improvement in Electric-Arc Lamps, of which the following description, in connection with the accompanying drawings, is a specification, like characters on the drawings representing like parts.

This invention relates more especially to that type of electric-arc lamps wherein carbon-rods are dispensed with, the upper carbon being carried by and longitudinally movable in 15 a tubular receiver or holder, one form of such type of lamp being shown in United States Patent No. 603,630, dated May 10, 1898, to which reference may be had.

Our present invention has for its more particular object the production of novel clutch mechanism for the upper carbon, which not only controls the feed of the carbon, but also prevents lateral movement thereof, while at the same time simplifying the construction 25 and arrangement of the parts. In arc-lamps of the type referred to it is now common to provide some form of guide for the carbon extraneous to the clutch mechanism, either as a member located some distance below the 30 clutch mechanism or coöperating with the said mechanism to guide it and prevent lateral movement. In either construction the use of a crooked carbon results in the binding or jamming of the clutch, preventing its 35 operation, or the carbon will be fed off to one side of the lower carbon, cutting off the arc. We have obviated these objectionable features by mounting the clutch mechanism wholly upon the tubular carbon-receiver, so 40 that being concentric therewith at all times it cannot become jammed by reason of a crooked carbon, and the construction of the clutch mechanism is such that a firm lateral support is given to the carbon, compelling its 45 feed movement in proper alinement with the lower carbon.

Various other features of our invention will be hereinafter described in the specification, and particularly pointed out in the claims.

50 Figure 1 represents in side elevation and

partly broken out an arc-lamp with clutch mechanism embodying our invention applied thereto, the outer globe and the lamp-case being shown in section. Fig. 2 is an enlarged side view of the clutch mechanism with the 55 parts in position to release the carbon. Fig. 3 is a side elevation thereof, partly broken out, the carbon-receiving tube being shown in section; and Fig. 4 shows the clutch mechanism in position to release the metallic car- 60 rier at the upper end of the carbon.

Referring to Fig. 1, the open body A, the series-wound and shunt coils, the latter being shown at C', the outer globe G^x, its supporting-socket A⁹, the inner globe G, the tubular receiver B for the upper carbon extending through the open body A and passing freely through its base A', and the resistance R R' may be and are all substantially as in United States Patent No. 603,630, referred to, 70 the same letters representing like parts herein. As in the said patent, the clutch mechanism is controlled by the movement of the tubular receiver B for the upper carbon L', the carrier for the latter being shown in Fig. 75 4 as a short metal tube a, tapered at its lower end at a' and embracing the upper end of the carbon. This carrier slides loosely and freely in the tube B and is electrically connected through the metal body of the lamp with the 80 line-wire l, as in the patent referred to.

The clutch mechanism comprises, essentially, two relatively movable yoke-like members mounted on the tube B, one being fixed thereupon, bell-crank levers being pivoted 85 on one member and connected by links with the other, clamping-jaws being fulcrumed on the lower ends of the levers. As herein shown, a split yoke-like member d is clamped by a suitable screw 2 upon the tube B a short 90 distance above its lower end, said member having diametrically opposite ears d', on which are fulcrumed two links d^x, the lower free ends of which are in turn jointed to the upper divergent arms of bell-crank levers d², 95 pivotedly mounted at d³ in a second yoke-like member. This member comprises a hub f, which embraces and is adapted to slide upon the end of the tube B below the member d, the hub having rigidly secured to or forming 100

part of it diametrically opposite downturned and preferably bifurcated arms f' , in which the bell-crank levers d^2 are pivotally mounted, as shown in Fig. 3. The arms f' extend 5 well below the hub f and obviously present rigid points of support for the said levers d^2 at opposite sides of the carbon, the lower end of the hub f being substantially at the extremity of the tube B when the clutch is in 10 engagement with the carbon. The jaws d^4 for clamping the upper carbon are pivoted to the lower ends of the bell-crank levers within the yoke-arms f' . When the tube B is lifted, the links d^5 act upon the outer 15 ends of the levers d^2 , causing their short arms to move down and inward to thereby clamp the jaws d^4 firmly upon the upper carbon and lift it, separating it from the lower carbon and forming the arc, the weight of 20 the hub f tending to always move it toward the lower end of the tube B in clamping position.

A cross-bar h is shown as secured to the depending rods A^5 , which support the globe-socket A^9 below the clutch mechanism, said bar having a central aperture for the upper carbon, while a hub h' is secured to or formed on the upper side of the bar around the aperture. This hub has an annular upturned 25 flange h^2 , which is in the path of the lower ends of the jaws d^4 , and when the tube B descends far enough the said flange engages the jaws and stops their downward movement, as well as the downward movement of 30 the yoke, unclamping the carbon, as the continued movement of the tube B causes the link d^5 to operate the bell-crank levers d^2 and open the jaws.

By mounting the clutch mechanism wholly 40 upon the tube B the jaws d^4 are always concentric with the tube and they cannot become jammed by a crooked carbon, while the rigid supports f' for the jaw-carrying levers d^2 at each side of the carbon serve to positively position and guide it, preventing any improper lateral movement thereof, the whole clutch mechanism partaking of all lateral movement, if any, of the tube B.

When the carbon-carrier a comes between 50 the clamping-jaws, they are more widely separated and lifted, owing to the larger external diameter of the carrier, so that the flange h^2 would not engage the jaws until the tube B had moved farther than when the jaws 55 were in engagement with the carbon. In order therefore to release the clutch without such increased movement of the carbon-receiving tube, the hub h' is provided with two upturned lugs h^3 , which are so located as to 60 strike the short arms of the bell-crank levers d^2 very near their fulcrum d^8 when the jaws engage the carrier a , as shown in Fig. 4. The lugs h^3 thus effect the releasing movement of the jaws much more rapidly than would the 65 flange h^2 acting on the jaws themselves and with a consequent reduced movement of the controlling-tube B.

From the foregoing description it will be seen that we have dispensed altogether with any guide for the carbon extraneous to the 70 clutch mechanism, the latter serving to guide laterally as well as to control the feed movement of the carbon.

Our invention is not restricted to the precise construction and arrangement of parts 75 as herein shown, as the same may be varied without departing from the spirit and scope of the invention.

Having described our invention, what we claim as new, and desire to secure by Letters 80 Patent, is—

1. In an electric-arc lamp, a tube for receiving and permitting vertical movement therein of the upper carbon, a clutch mounted wholly upon said tube, and means for preventing lateral movement of the clutch relatively to the axis of the tube. 85

2. In an electric-arc lamp, a tube for the upper carbon, a support mounted to slide upon said tube and having opposite, depending arms, and clamping means for the carbon, pivotally mounted on said arms below the tube and preventing lateral movement of 90 the carbon.

3. In an electric-arc lamp, a tube for the upper carbon, and a clutch mounted wholly on said tube, the clutch including clamping-jaws for the carbon, and a supporting member for said jaws, concentric with and longitudinally guided by the tube and movable 100 thereon, to control the feed of and position the carbon laterally.

4. In an electric-arc lamp, a tube for receiving and permitting vertical movement therein of the upper carbon, clutch mechanism including two relatively-movable members mounted on the tube one in sliding relation thereto, jaws carried by one of said members below the end of the tube, to engage the carbon, and connections between 110 said jaws and the other member, whereby relative movement of said members will cause said jaws to clamp or release the carbon. 105

5. In an electric-arc lamp, a tubular receiver for and in which the upper carbon is 115 vertically movable, and a clutch mounted wholly upon the receiver, said clutch comprising a yoke adapted to slide on the receiver and having lateral arms depending below the tube, bell-crank levers fulcrumed on said arms, clamping-jaws pivotally mounted on 120 said levers and adapted to clamp the carbon, and operating-links pivotally connected with the outer ends of the levers and to the tubular receiver. 125

6. In an electric-arc lamp, a tube to receive and permit vertical movement therein of the upper carbon, and a clutch mounted wholly upon the tube, said clutch comprising clamping means for the carbon, a support therefor mounted to slide on the tube, connections between said clamping means and the tube, fulcrumed upon the latter, and a fixed stop to engage said clamping means and move the 130

support on the tube, to thereby release the carbon.

7. In an electric-arc lamp, a tube to receive and permit vertical movement therein of the upper carbon, and a clutch mounted wholly upon the tube, said clutch comprising clamping-jaws for the carbon, levers upon which the jaws are pivoted, a support for said levers, mounted to slide upon the tube, links connecting the tube and the outer ends of the latter, a fixed stop to normally engage the jaws and move the support on the tube, to release the carbon, and auxiliary means to engage and move the levers when the jaws are in engagement with and more widely separated by the carrier attached to the upper end of the carbon.

8. In an electric-arc lamp, a carbon-receiving tube, and a clutch mechanism consisting of two relatively-movable yoke-like members mounted upon said tube one in sliding relation thereto, bell-crank levers pivotally mounted on one member and having clamping-jaws

pivoted upon their lower ends, and links fulcrumed at one end on the other yoke-like member and pivotally connected at their other ends with the upper portions of said levers.

9. In an electric-arc lamp, a movable tubular controlling member for the upper carbon, and in which the latter is vertically movable, a clutch mechanism carried wholly by said controlling member, the clutch being positively held against lateral shifting, and a fixed stop mounted independently of and to engage the clutch mechanism to release the carbon.

In testimony whereof we have signed our names to this specification in the presence of two subscribing witnesses.
